DESIGN FOR A TEXTILE FABRIC OR THE LIKE

Robert C. Kahrmann, Elizabeth, N. J., assignor to Joseph W. Woods Company, Inc., New York,
N. Y., a corporation of New York

Application March 15, 1934, Serial No. 51,065

Term of patent 3½ years

To all whom it may concern:

Be it known that I, ROBERT C. KAHRMANN, a citizen of the United States of America and a resident of the town of Elizabeth, county of Union, and State of New Jersey, have invented a new, original, and ornamental Design for a Textile Fabric or the like, of which the following is a specification, reference being had to the accompanying drawing forming part hereof.

The figure is a drawing of a textile fabric embodying my new design. The design shown is intended to recur in repetition on a strip of textile fabric.

I claim:

The ornamental design for a textile fabric or the like, as described and shown.

ROBERT C. KAHRMANN.
